UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

TOOL-RETAINER.

1,212,272.

Specification of Letters Patent. Patented Jan. 16, 1917.

Application filed August 29, 1916. Serial No. 117,484.

To all whom it may concern:

Be it known that I, WILLIAM A. SMITH, a citizen of the United States, residing at Denver, in the county of Denver and State 5 of Colorado, have invented certain new and useful Improvements in Tool-Retainers, of which the following is a specification.

The present invention relates to tool retaining means, and while particularly intended for rock drills, is not necessarily limited thereto.

One of the primary objects of the present invention is to provide a simple, practicable and effective structure, which will retain a 15 tool in its holder, and yet allow the necessary play of the latter for operating purposes, the device thus being especially useful in connection with hammers of the fluid pressure operated type.

20 A further object is to provide elements which form a part of the retaining means, and which will effectively secure said retaining means in its operative or its inoperative position, so that the apparatus may be used 25 with the retaining means in either position.

An embodiment of the invention is illustrated in the accompanying drawings, wherein:

Figure 1 is a side elevation of a portion 30 of the apparatus showing the retainer in place. Fig. 2 is a bottom plan view of the same. Fig. 3 is a front elevation. Fig. 4 is a detail sectional view through one of the ears.

35 Similar reference numerals designate corresponding parts in all the figures of the drawings.

In the embodiment illustrated, a motor head 5 is disclosed, which constitutes a tool 40 holding member, being provided with the usual socket to loosely receive a tool, a portion of such tool being shown at 6 and being in the form of a drill bit. This tool has an annular enlargement 7 which not only limits the inward movement of the tool into 45 the holding member 5, but is also adapted to be engaged by the tool retainer herein-after described. The tool holding member 5 is provided on opposite sides with outstanding integral, and therefore fixed ears 8, each having an opening 9 therethrough and which as shown in Fig. 3 comprises a contracted central portion with flaring mouths. The front face of each ear is furthermore 55 provided with angularly disposed faces 10

and 11 forming seats, and the rear side of each ear is also provided with angularly disposed faces 12 and 13 also forming seats, the faces 10 and 11 being parallel, and the faces 11 and 13 being also preferably disposed in parallel relation.

The tool retaining member consists of a yoke comprising a cross head or bar 14 notched as illustrated at 15, so that it will partially surround the shank of the drill bit 65 6, the notch being sufficiently large to permit the free play of said drill bit, but also sufficiently small to insure the cross head being engaged by the enlargement 7, said enlargement being located between the cross head 70 or bar 14 and the front end of the tool holding member 5. Secured in the ends of the cross head or bar 14 are rearwardly extending arms 16 that are outwardly curved so as to escape the tool-holding member 5, said 75 arms passing through the openings 9 in the ears 8 and pivotally engaged therein so that they swing on an axis transverse to the tool holding member 5, and consequently to a tool, as 6, placed in said member. It so will be seen that the flaring formation of the opening 9, as illustrated in Fig. 3, permits this pivotal movement.

The arms 16 are provided with enlargements 17 forming abutments that are arranged to bear against the seats 10 or 11, accordingly as the tool retaining member is swung to its operative or inoperative position, and washers 18 mounted on the rear portions of the arms 16, are in like manner 85 arranged to bear against the seats 12 and 13. These washers are yieldingly urged to seating position by coiled springs 19 mounted on the rear ends of the arms and held in place by washers 20 and nuts 21, the nuts, in turn, 90 being secured against accidental displacement by pins 22.

It will be obvious that this construction is very simple and it is also thoroughly practical. When the tool retaining member is 100 disposed in the position shown in full lines in the drawings it will allow a free limited play of the tool, but will prevent its entire detachment from the tool holding member 5. If struck by the enlargement 7 the springs 105 19 permit it to afford a yielding resistance to the blow. If the retaining member is swung to the position shown in dotted lines, it is positively held in said position, thereby being disposed out of the path of the 110

enlargement 7 of the tool 6, so that said tool can be easily withdrawn or replaced, and also permitting the apparatus to be used with the retainer inactive.

5 From the foregoing it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

15 Having thus fully described my invention, what I claim as new, and desire to secure by Letters Patent, is:

1. In apparatus of the character set forth, the combination with a tool holding member, 20 of a swinging tool retaining member mounted on the tool holding member and having its axis disposed transversely thereto, one of said members having angularly disposed seats, against which the other member bears 25 accordingly as the retaining member is in its operative or inoperative position, and means for yieldingly urging the members into seating engagement to maintain the retaining member in both of said positions.

30 2. In apparatus of the character set forth, the combination with a tool holding member, of a swinging tool retaining member mounted on the tool holding member and having its axis disposed transversely thereto, said tool holding member having angularly disposed seats against which the tool retaining member is adapted to bear accordingly as said member is in its operative or inoperative position, and means for yieldingly urging 35 the tool retaining member against said seats to hold said member in both its operative and inoperative positions.

35 3. In apparatus of the character set forth, the combination with a tool holding member having an ear, a tool retaining member mounted on the ear and swinging on an axis intersecting the ear and transverse to a tool mounted in the tool holding member, and co- 40 acting elements on the ear and tool retaining member to hold the latter either in an operative or inoperative position with respect to the tool.

45 4. In apparatus of the character set forth, a tool holding member having an ear and a swinging tool retaining member passing through the ear and having a pivotal movement therein on an axis intersecting the ear and transverse to a tool placed in the tool holding member.

50 5. In apparatus of the character set forth, a tool holding member including an element having an opening therein disposed longitudinally of a tool held by said member and a tool retaining member having an element engaged in the opening and pivotally mounted

therein, said element having a swinging movement on an axis transverse to a tool placed in the tool holding member and swinging in a plane disposed substantially longitudinally of such tool.

55 6. In apparatus of the character set forth, a tool holding member including an element having an opening therein, a tool retaining member having an element slidably and pivotally engaged in the opening, said element having a swinging movement on an axis transverse to the tool holding member, and means for yieldingly resisting such sliding movement.

70 7. In apparatus of the character set forth, a tool holding member having an ear provided with an opening, a tool retaining member having an arm slidably passing through the opening and swinging therein on an axis transverse to the tool holding member, and a spring for yieldingly resisting the sliding movement while permitting the swinging movement of the same.

75 8. In apparatus of the character set forth, a tool holding member having fixed elements on opposite portions thereof provided with openings, and a tool retaining yoke having spaced side arms entering said openings and slidably mounted therein.

80 9. In apparatus of the character set forth, a tool holding member having fixed elements on opposite portions thereof provided with openings, a tool retaining yoke having spaced side arms entering said openings and slidably mounted therein, and means for yieldingly resisting said sliding movement.

85 10. In apparatus of the character set forth, a tool holding member having elements on opposite sides thereof provided with openings disposed longitudinally of a tool held by said member, and a tool retaining yoke having spaced side arms entering said openings and pivotally mounted therein.

90 11. In apparatus of the character set forth, a tool holding member provided with offset 110 outstanding ears, a tool retaining yoke having spaced side arms slidably and pivotally passing through said ears, and springs on the side arms for yieldingly resisting said sliding movement.

115 12. In apparatus of the character set forth, a tool holding member provided with oppositely outstanding ears, a tool retaining yoke having spaced side arms slidably passing through said ears and having a pivotal movement therein, stops on the side arms engaging the fronts of said ears to limit the rearward movement of the yoke, and coiled springs on the arms bearing against the rear sides of the ears to yieldingly resist the forward movement of the yoke.

120 13. In apparatus of the character set forth, a tool holding member having an ear provided with angularly disposed seats on one 125 face, a tool retaining member having an arm

passing through the ear and pivoted thereon on an axis transverse to the tool holding member, said arm having a stop arranged to engage the seats accordingly as the tool retaining member is swung to an operative or an inoperative position, and a spring on the arm for urging the stop against the seats.

14. In apparatus of the character set forth, a tool holding member having oppositely disposed outstanding ears provided with openings and angularly disposed seats on their opposite faces, a tool retaining yoke having spaced arms passing through the

openings in the ears and pivoted therein on an axis transverse to the tool holding member, said arms having stops arranged to engage the seats on the front faces of the ears, washers that engage the corresponding rear faces, and coiled springs on the rear ends of the arms bearing against the washers.

In testimony whereof, I affix my signature in the presence of two witnesses.

WILLIAM A. SMITH.
